UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

MEANS FOR AND METHOD OF APPLYING ANTIOFFSET MATERIAL TO FRESHLY-PRINTED SHEETS.

Application filed February 20, 1922. Serial No. 537,834.

To all whom it may concern:

Be it known that I, HOWARD M. BARBER, a citizen of the United States, and resident of Stonington, in the county of New London and State of Connecticut, have invented a new and useful Improvement in Means for and Methods of Applying Antioffset Material to Freshly-Printed Sheets, of which the following is a specification.

10 In the printing art it frequently happens that only a portion or portions of a freshly printed sheet requires the use of an anti-offsetting medium, as for instance where only a portion or portions of the sheet are printed or where only a portion or portions of the sheet are heavily printed and the balance of the sheet lightly printed. Slip sheets must be substantially the size of the printed sheets and the slip sheets are not only expensive 15 or where only a portion or portions of the sheet are heavily printed and the balance of the sheet lightly printed. Slip sheets must be substantially the size of the printed sheets and the slip sheets are not only expensive 20 but require complicated machinery for properly introducing them between and separating them from the printed sheets. Where anti-offset material has been used heretofore, it has been applied to the entire sheet 25 and not only results in a considerable expense, but also requires the use of complicated apparatus for removing the surplus material from the sheets.

The object of my invention therefore is to 30 provide a novel means for and method of treating freshly printed sheets especially color sheets, by applying an anti-offset material in liquid or powder form onto a predetermined portion or portions of the freshly 35 printed sheet to prevent the portion or portions of the sheet from offsetting.

My invention includes means whereby predetermined heavily printed portions of the freshly printed sheets are treated to prevent 40 offset, leaving the lightly printed or unprinted portions of the sheet untreated.

My invention more particularly includes 45 providing a member with one or more relief portions corresponding in outline to and adapted to register with a predetermined heavily printed portion or portions of the freshly printed sheet, means being employed for applying the anti-offset material in liquid or powder form to the said relief portion or portions for transfer thereby onto 50 said predetermined heavily printed portion or portions of the sheet.

A practical embodiment of my invention is represented in the accompanying draw-

ings, in which the invention is shown as applied to a multi-color rotary sheet printing press.

Fig. 1 represents a longitudinal vertical central section through a portion of a multi-color printing press with my anti-offset material applying mechanism shown in connection therewith.

Fig. 2 represents an exaggerated detail section of the anti-offset material applying mechanism.

Fig. 3 represents a plan view of a proof which may be used in connection with the anti-offset material applying cylinder.

The printing mechanism herein shown comprises an impression cylinder 1, around 70 which are grouped four plate cylinders 2, 3, 4, 5. The impression cylinder is herein shown as having two impression surfaces 6 and 7 with their respective sheet carrying head grippers 8 and 9. The sheet feed cylinder 10 is provided with a set of head grippers 11 for feeding the sheets from any suitable source of supply to the impression cylinder. The printed sheet delivery reel 12, 75 may be provided with a set of head grippers 13 for taking the freshly printed sheets from the impression cylinder and delivering them to any suitable point.

The means which I have shown for applying anti-offset material either in liquid 80 or powder form to a predetermined portion or portions of the freshly printed sheet, is herein shown as a rotary cylinder 14 having one or more relief portions corresponding in outline to and in registry with the predetermined heavily printed portion or portions of the freshly printed sheet, said cylinder 14 being arranged to coact with the impression cylinder 1 for applying the anti-offset material while the freshly printed sheet is still 90 carried by the impression cylinder.

One way of providing the cylinder 14 with a relief portion or portions would be to wrap the proof 15 around the cylinder 14 in registry with the freshly printed sheet 100 and then build up the required portions of the proof to form reliefs, such as 16 and 17, corresponding in outline to the portions of the freshly printed sheet to which it is desired to apply the anti-offset material. 105

The anti-offset material in liquid or powder form is contained in a reservoir 18; rolls 19 and 20 being provided for trans-

ferring the anti-offset material from the reservoir to the relief portions 16, 17 on the cylinder 14, for transfer thereby onto the heavily printed portions of the freshly 5 printed sheet as the sheet passes from the fast plate cylinder 5 to the delivery reel 12. The cylinder 20 is carried in adjustable bearings 21 so that it may be set in proper adjustment to both the roll 19 and the relief 10 form carried by the cylinder 14. It may be desirable to use a blade 22 for regulating the supply of the anti-offset material from the cylinder 19 to the cylinder 20.

From the above description it will be seen that by the use of my invention I am enabled to apply anti-offset material in liquid or powder form to that portion or portions only of the freshly printed sheet which require treatment to prevent offset in the delivery 15 of the sheet. This arrangement results in a considerable saving of the anti-offset material, which is of great importance, and also eliminates the necessity of utilizing complicated and expensive machinery for removing excess anti-offset material from the freshly printed sheet.

This invention is particularly well adapted for use in connection with color work where certain portions of the sheet are provided with much heavier application of the color than other portions thereof, said heavier portions being the ones which require treatment for preventing offset.

It is evident that various changes may be made in the construction, form and arrangement of the several parts without departing from the spirit and scope of my invention, hence, I do not wish to limit myself to the particular embodiment herein shown and described, but

What I claim is:—

1. Sheet printing mechanism and means coacting therewith for applying anti-offset material onto predetermined freshly printed portions only of the sheets.
2. Sheet printing mechanism and means coacting therewith for applying anti-offset material onto freshly heavily printed portions only of the sheets.
3. An impression cylinder, one or more form cylinders coacting therewith to print

sheets, and means coacting with the impression cylinder for applying anti-offset material onto predetermined portions only of the sheets.

4. An impression cylinder, one or more form cylinders coacting therewith to print sheets, and means coacting with the impression cylinder for applying anti-offset material onto predetermined heavily printed portions only of the sheets.

5. An impression cylinder, one or more form cylinders coacting therewith to print a sheet, a cylinder coacting with the impression cylinder and having a relief portion corresponding in outline to and in registry with the freshly printed portion of the sheet to which the anti-offset material is to be applied, and means for applying the anti-offset material onto said relief portion for transfer thereby onto the sheet.

6. An impression cylinder, one or more form cylinders coacting therewith to print a sheet, a cylinder coacting with the impression cylinder and having a proof applied thereto in registry with the freshly printed sheet, said proof having a relief portion corresponding in outline to that portion of the sheet to which the anti-offset material is to be applied, and means for applying the anti-offset material onto said relief portion for transfer thereby onto the sheet.

7. The method of preventing offset of freshly printed sheets consisting in applying anti-offset material onto predetermined portions only of the sheets.

8. The method of preventing offset of freshly printed sheets consisting in applying anti-offset material onto predetermined heavily printed portions only of the sheets.

9. The method of preventing offset of freshly printed sheets comprising, producing a member having a relief portion corresponding to and in registry with a predetermined portion of the sheet, applying anti-offset material to the relief portion, and transferring the anti-offset material onto the corresponding portion of the sheet.

In testimony, that I claim the foregoing as my invention, I have signed my name this 17th day of February A. D. 1922.

HOWARD M. BARBER.
